DESIGN FOR A FRAME FOR SPECTACLES

Lawrence R. Collins, Richmond, Va.

Application March 5, 1942, Serial No. 106,091

Term of patent 7 years

To all whom it may concern:

Be it known that I, Lawrence R. Collins, a citizen of the United States, residing at Richmond, in the State of Virginia, have invented a new, original, and ornamental Design for Frames for Spectacles, of which the following is a specification, reference being had to the accompanying drawing, forming a part thereof.

Figure I is a plan view of the frame for spectacles, showing my new design; and Figure II is the front elevational view of the same.

I claim:

The ornamental design for a frame for spectacles, as shown and described.

LAWRENCE R. COLLINS.
